UNITED STATES PATENT OFFICE.

FREDRICK W. NITTEL, OF ATTLEBORO FALLS, MASSACHUSETTS, ASSIGNOR TO M S COMPANY, OF ATTLEBORO, MASSACHUSETTS.

EXPANSIBLE BRACELET.

Application filed June 3, 1926. Serial No. 113,420.

This invention relates to certain new and useful improvements in expandable bracelets, and the primary object thereof is to provide a bracelet wherein the links can be easily and quickly assembled, or removed, or applied in order to shorten or lengthen the bracelet.

A further object of the invention is to provide a bracelet which can be manufactured without the use of solder.

The invention still further aims to provide a bracelet wherein the links are adaptable for construction from perforate as well as imperforate material.

Still further, the invention aims to provide a bracelet where in the links involve a minimum of parts that are compactly assembled.

In the drawings:—

Fig. 1 is a bottom plan view, partly broken away and in section of several of the links;

Fig. 2 is a section on line 2—2 of Fig. 1 and

Figs. 3 and 4 are sections on lines 3—3 and 4—4 respectively of Fig. 2;

Fig. 5 is a detail perspective view of one of the boxes and

Fig. 6 is a like view of one of the connectors.

In proceeding in accordance with the present invention but three parts are employed, namely a box 1 a connector 2 and a coil spring 3. As shown in Fig. 5 of the drawings each box has a bottom 4, end walls 5, one of which has ears 10, and side walls 6, the whole being made of a single piece of metal with sides and ends bent into the form shown. The side edges of the sides 6 are turned inwardly to form flanges 7 which latter are disposed above the free upper edges of the ends 5. The connectors 2 are formed of plates which have a down-turned flange 8 at one end, and the sides of the body of the plate at the opposite end 11 are formed with oppositely disposed notches 9. In assembly the connector plates 2 are engaged beneath the flanges 7 and the upper free side edges of the one of the ends 5 the coil spring 3 being engaged between the bottoms 4 of the boxes and the plates 2, and at one end abut the flanges 8 of the plates 2 and at their opposite ends abut the adjacent ends of the boxes. It is understood of course that the sides of the boxes are in this

assembly in the dotted line position of Fig. 5, while the coil springs and the connectors are related to the boxes, following which the sides are bent inwardly to the full line position of Fig. 5, to form the flanges 7. Thus each link consists of but three parts that are assembled without the use of solder. To connect the links one to the other it is merely necessary to move the connectors 2 of the adjacent link against the tension of the springs 3 thereof, as to expose the notches 9 and the end wall 5 that carries extensions 10 forming hinging ears, whereupon the end of the connector having the notches 9 is held at right angles and at an incline with respect to the transverse plane of the bottom 4 of the box and is then moved to be in such plane to cause its notches 9 to receive the opposed flanges 7 of the box, whereupon the connector is moved to lie parallel to or in the plane of the box, and the parts released so that the flange 8 of the adjacent connector will engage the end 11 of the first connector and hold same against turning movement to disconnect the parts.

It will also be apparent from the foregoing that the parts can be made of perforate or imperforate material and that the same may be as easily disconnected by a reverse movement of the connector. It will also be understood that when assembled the bottom of the boxes occur at and form a part of the top of the bracelet.

Having thus described my invention, what I claim as new and desire to secure by Letters Patent:—

1. In a bracelet, links having boxes, ears on the upper edge of an end of each box projecting above such edge, inwardly extending flanges on the box sides overlying the ears at one end of the box and having their opposite ends free and spaced above the upper edge of the opposite end of the box, and a spring pressed connector in each box having cut-outs in its sides formed to receive the flanges and ears, the cut-outs and flanges being related so as to permit the connector to be held at right angles to the plane of the box thereby to receive the flanges in the cut-outs, and allow the connector to be moved along the flanges to cause the ears to be received in the cut-outs and thereupon permit the connector to be moved into the plane of the box.

2. In a bracelet, links having boxes, ears

on the upper edge of an end of each box projecting above such edge, and a spring pressed connector in each box having cut-out parts in its sides and adjacent an end 5 of the connector, and flanges on the box sides, said cut-outs and the flanges being disposed whereby to require the connector to be placed at right angles to the plane of the box and at an acute angle to a line drawn

at true right angles across the box so as to 10 permit the cut-outs to receive the flanges and the connector to be moved into said line and then swung to lie in the plane of the box and with the ears received in the cut-outs.

In testimony whereof I have signed my 15 name to this specification.

FREDRICK W. NITTEL.
